UNITED STATES PATENT OFFICE.

CHARLES C. RUEGER, OF BUTTE, MONTANA.

POCKET-COMPASS.

SPECIFICATION forming part of Letters Patent No. 709,046, dated September 16, 1902.

Application filed July 16, 1901. Serial No. 68,505. (No model.)

To all whom it may concern:

Be it known that I, CHARLES C. RUEGER, a citizen of the United States, residing at Butte, in the county of Silverbow and State of Montana, have invented certain new and useful Improvements in Pocket-Compasses; and I do hereby declare the following to be a full, clear, and exact description of the invention, such as will enable others skilled in the art to which it appertains to make and use the same.

My invention consists in the novel features hereinafter described, reference being had to the accompanying drawings, which illustrate one form in which I have contemplated embodying my invention, and the said invention is fully disclosed in the following description and claims.

Referring to the drawings, Figure 1 represents a top plan view of my improved compass drawn to a larger scale than the actual size, the folding diopters being removed. Fig. 1^a represents a central section through the level attached to the instrument. Fig. 1^b represents an end view of the level, showing in detail the attaching-screw and eccentric sleeve. Fig. 2 represents a central vertical section through the instrument, showing the diopters in place and folded down upon the top of the instrument. Fig. 3 is a partial side elevation of the instrument, showing the arrangement of the indicating-marks on its exterior. Fig. 4 is a partial sectional view of the clinometer-disk, showing the graduations thereon. Fig. 5 represents a sectional view of one side of the compass-casing and leveling-ring, showing a method of attaching the parts together. Figs. 6 and 7 are detail views of the two diopters. Fig. 8 is a detail view, partly in section, showing the devices for attaching the level to its ring and for adjusting it.

The object of my invention is to provide a pocket instrument of moderate size which will permit with the greatest convenience and sufficient accuracy those angular measurements which the practical mining engineer is most frequently required to make, and the device is adapted for use under ground as well as upon the surface.

In the drawings, A represents the compass-casing, which is provided with a flush glass cover B, having its edges beveled, as indi-

cated in the drawings, Fig. 2, and secured in place by means of a friction retaining-ring b, adapted to fit snugly within the upper part of the casing and flush therewith and having its inner face or periphery beveled to overhang the beveled edge of the glass cover, and thus retain it in position. This construction provides the compass with a flush upper surface having no projecting parts to obstruct the view and which is readily kept clean. In the use of these instruments under ground particularly dirt, water, grease from candles, and other foreign matter frequently drop upon the glass cover, and it is at once apparent how much the flush top facilitates the quick removal of such substances as well as the general cleanliness of the instrument. It is also highly important to prevent so far as possible corrosive waters from getting into the interior of the compass-casing, and the flush top is distinctly advantageous in preventing this. Moreover, as the ring b is held in place by friction only the glass cover may be quickly and easily removed without the use of tools for the purpose of cleaning the interior of the compass-casing should any corrosive material find an entrance to the interior or whenever it is desirable to obtain access to the interior for any purpose—as, for example, to make a change in the style of division-numbering, as hereinafter explained. The bottom of the compass-casing is provided with a threaded aperture b', which is engaged by an adjusting-screw c, having a milled head c, forming a shoulder to prevent overwinding of the screw. This screw c is provided with a threaded central aperture, in which is located the threaded portions of the center pin d, which is provided with a milled head d' and a shoulder d'', adapted to engage the screw c to prevent overwinding of the center pin. Within the compass-casing is a revoluble plate or disk C, which I term for convenience of reference the "clinometer-disk." This disk has a central bearing engaging the center pin d and resting upon the screw c, and said disk is also provided with a peripheral vertical flange c², terminating at its upper edge in a horizontal outwardly-projecting flange c³. The disk C is also provided at one point near its periphery with a weight c⁴ for use when the device

is used in clinometer work. The weight c^4 is attached to the disk C by means of a screw c^x , passing eccentrically through said weight. By loosening the screw and moving the weight 5 slightly to one side or the other a very delicate and accurate adjustment of the disk with reference to the compass-casing can be obtained, after which the screw is tightened to hold the weight in its adjusted position. 10 The disk C is provided with graduations on its upper face and upon the upper face of the flange c^3 , corresponding therewith, as shown in Fig. 1, and with corresponding graduations on the inner face of the vertical flange c^2 , as 15 shown in Fig. 4. This construction of disk gives ample space on the disk proper for two or more styles of numbering, which may be made in different colors, if desired. The divisions on the vertical flange avoid errors of 20 parallax in reading the needle, and the divisions on the flange of the disk facilitate the adjustment of the disk with respect to the quadrant-marks on the compass-casing and also the clinometer-readings on the disk. By 25 means of the screw c the disk C may be held from rotation by forcing it upward until the flange c^3 is pressed into engagement with the glass cover B, or said disk may be released, so as to revolve upon the center pin, as will 30 be readily understood from the drawings. It will be understood that the graduation or division numberings shown in Fig. 1 are incomplete, as will be evident to those familiar with such instrument, different styles of 35 numbering being illustrated on portions of the disk to avoid confusion.

D represents the magnetic needle, which is provided with an agate seat d^3 , engaging the center pin, the arms of the needle on each 40 side of the center pin being curved, as shown in Fig. 2. By turning the center pin d the needle may be allowed to swing freely or may be pressed upward against the glass cover B to hold it from movement. By making the 45 needle curved, as shown, with the curved portions extending slightly above the seat it will be seen that when the needle is raised the curved arms will engage the glass cover with a slight spring-pressure before the seat is 50 raised into contact with the glass, and the shoulder d^2 will prevent the seat from being brought into contact with the glass cover, thus protecting the point of the center pin. By making the disk C, which carries the 55 graduations, revolvable within the compass-casing it will be seen that the disk can be adjusted to set off the magnetic variations, so as to allow needle-readings to be taken from the true meridian, and by providing the disk with 60 the weight c^4 it can also be used as a clinometer. By the mechanism above described both the needle and the clinometer-disk can be arrested without perceptible change of position, so as to preserve their readings, thus allowing 65 readings to be taken from the arrested parts where it is difficult to obtain them at the

time of making the observation or allowing readings taken at the time of observation to be checked by readings taken from the arrested parts. The disk C has a further advantage in that it permits a variety of circle division-numberings being used without interfering with the principal division-lines, which are engraved or marked in any suitable manner upon the inner face and top of the 75 flanges c^2 and c^3 , respectively, preferably at intervals of five degrees. This result may be simply and cheaply secured by pasting or otherwise securing to the face of the disk an auxiliary disk of paper or other suitable material on which is marked the style of division-numbering which suits the particular user of the instrument. As the possible styles of division-numbering are limited in number, the manufacturer of the instrument can readily and cheaply supply a set of auxiliary disks, which will enable the owner of the instrument to use one or other of them at his pleasure. 80

To the rim of the compass-casing are pivoted on opposite sides the folding diopters E and F, each of which is provided at its upper end with a hook e and f , respectively, by means of which the compass may be hung upon a string or wire stretched between survey-stations after the manner of the German miner's compass. Each of the diopters is provided at its lower end with bifurcated portions e' and f' , respectively, which permit of an unobstructed view between them. The dipter E is provided with a mirror e^2 , having a central vertical sight-line engraved or otherwise affixed thereon. The upper part of the dipter F consists of a vertical standard f^2 , which can be used as a sight when desired. The diopters E and F may be folded 95 down upon the top of the compass, as shown in Fig. 2, and they may also be swung over laterally and their points allowed to touch a table or other support when the apparatus is used upon a drawing board or table for the 100 purpose of determining angles, as hereinafter described. The top of the compass-casing is preferably provided with a pair of detachable plates $a a$, provided with perforated ears $a' a'$ to receive the pivoted diopters, and said 105 plates are detachably secured to the compass-casing by screws $a^2 a^2$, so that these plates and the diopters may be removed from the 110 compass-casing, if desired. 115

The exterior of the compass-casing is provided with an annular revolvable ring G, (see Fig. 2,) to which is secured adjustably a level or bubble-tube g . (See Fig. 1.) I prefer to attach the tube g adjustably to the ring G by the following mechanism: The 120 ring G is provided centrally with a pin g' , which engages an aperture in the tube g , said aperture being made a little wider at its mouth than the pin g' in the plane of the ring G. At each end the tube g is provided with a yoke g^2 , adapted to receive an 125 eccentric sleeve g^3 between its bifurcated por- 130

tions, said sleeve being held in place by an adjusting-screw g^4 , passing through the eccentric sleeve and having its head engaging the upper face of the yoke. Each of the 5 sleeves is provided with an aperture g^5 in its side to permit the insertion of a tool for rotating the sleeve to adjust the tube g in a direction perpendicular to the face of the compass, and by loosening one of the adjusting- 10 screws g^4 and tightening the other the tube g may be adjusted in the plane of the face of the compass. The projecting peripheral portions of the ring G are preferably milled to facilitate the turning of the ring around 15 the compass-casing, and the exterior of said ring is provided with four quadrant-marks, (see i , Fig. 3,) the milled surface being cut away to allow these marks to be plainly seen. These quadrant-marks can be brought into 20 alignment with similar quadrant-marks on the top face of the compass-casing, which are also carried down onto the outer peripheral edge of the casing. This leveling-ring may be used for the purpose of leveling the face 25 of the compass and may be also utilized when the device is used as a clinometer. The quadrant-points on the ring G give readings 30 on the circle division-line cut into the outside periphery of the compass-casing. For convenience in using the instrument in clinometer work and for other purposes another sight-line is provided, which consists of a heavy line b' , which is engraved in the glass cover and blackened or otherwise treated 35 to render it distinct. This line b' is coincident with the sight-line of the diopters and in case the diopters are removed will form the guiding line of sight for the determination 40 of horizontal and vertical angles.

40 In order to illuminate the compass when it is used for underground purposes, I provide a gasolene-torch H , revolvably secured to the bottom of the compass and provided with a wick-tube H' and a closing device H^2 . The 45 interior of the body of the torch and the wick-tube are preferably filled with wicking which is saturated with gasolene or other suitable fluid, so that by lighting the portion of the wick projecting from the wick-tube 50 which extends up slightly above the plane of the top of the compass the compass will be illuminated. The main body of the torch, which is of circular shape, is preferably provided with three or more supporting lugs or 55 feet h , which will support the instrument when it is placed upon a table, when it will be seen that the compass-body may be rotated upon the torch. This construction is 60 convenient when it is desired to use the instrument in platting surveys, in which case the compass-casing can be turned easily and accurately into the desired position for the needle and the folding diopters may be swung over and downward until their points rest 65 upon the paper. By indicating these points

on the paper a line connecting them will give the desired bearing.

In the construction shown in Fig. 2 it will be observed that the annular body of the torch H extends outward beyond the bottom 70 of the ring G , so as to prevent the latter from being disengaged from the compass-casing. I may, however, provide the compass-casing with an annular groove a^3 (see Fig. 5) and provide the ring G with four screws g^6 , projecting into said groove, in order to attach the ring to the compass-casing while permitting it to revolve thereon. In such case it will be obvious that the torch H could be removed from the instrument, if desired. In 80 order to provide for the easy removal of the torch, I provide the annular body of the torch with a central circular aperture which engages an annular hub or boss a^4 on the bottom of the compass-casing, said hub or boss 85 being provided with a retaining-ring a^5 , secured thereto by means of screws a^6 , said retaining-ring engaging portions of the torch-body surrounding said hub and holding it in place. To remove the torch, it is only necessary to unscrew the screws a^6 and remove the retaining-ring a^5 .

The manifold uses to which the instrument may be put need not be particularly described herein, as they will be readily understood by 95 those skilled in the art to which this invention appertains. I will, however, indicate two ways in which the instrument may be used in clinometer work. According to the first the instrument is held in a vertical position. The sight-line of the instrument, which is given by the line on the glass cover or the diopters, is alined with the eye and the next station-point. The ring G is then rotated about the compass-casing so as to bring 100 the bubble-tube g to the top, and the ring is then carefully adjusted to bring the bubble in the center of the tube, (indicated by a mark on the glass,) at the same time retaining the alinement with the eye. The index-points on 105 ring G will then be read on the graduations on the exterior of the casing to give the angles of departure of the sight-line from the vertical and horizontal. The ring G will be held by friction from movement on the casing 110 unless it is carelessly handled or moved purposely. It is sometimes desirable to take observations while facing the instrument, in which case it is held with the glass cover facing the observer and the sight-line on the 115 cover is made to coincide with the line the inclination of which is to be determined. Ring G is then revolved on the casing and the bubble centered in the bubble-tube, and 120 readings are taken, as before described. A 125 more rapid though less sensitive clinometer-reading can be taken from the disk C . The alinement of the sight-line is effected as before described. The disk C is released and the 130 weight will seek the point directly below the

center of the disk, swinging the disk into position, so that the observer may take readings therefrom. In order to enable the observer to keep his eye at the sight-line, it is 5 preferable to arrest the disk when it has adjusted itself and take readings from the arrested disk.

What I claim, and desire to secure by Letters Patent, is—

1. The combination with a compass-casing, of a graduated disk revolvably mounted upon a central spindle within said casing, the casing inclosing said disk at the bottom and sides but being open at the top whereby the

15 entire upper face of said disk is exposed to view, a magnetic needle revolvably mounted above and independently of said disk, and adapted to read over the entire upper face of the disk at all times, and arresting devices 20 for said disk, substantially as described.

2. The combination with a compass-casing, of a graduated disk revolvably mounted upon a central spindle within said casing, the casing inclosing said disk at the bottom and 25 sides but being open at the top, whereby the entire upper face of said disk is exposed to view, a magnetic needle revolvably mounted above and independently of said disk, and adapted to read over the entire upper face 30 of the disk at all times, arresting devices for said disk and independent arresting devices for said needle, substantially as described.

3. In a compass, the combination with the casing, of a pivotally-mounted disk within 35 said casing, provided with portions adapted to engage the top of the casing to arrest said disk, an adjusting-screw for raising said disk to bring said portions into engagement with the top of the casing, a center pin having a 40 threaded portion passing through said adjusting-screw, and a needle mounted on said center pin above said disk whereby said center pin may be adjusted to raise the needle into contact with the top of the casing, sub- 45 stantially as described.

4. In a compass, the combination with the casing, of a pivotally-mounted disk within the casing provided with a vertically-disposed flange terminating at its upper end in a horizontal flange, and provided with a scale of 50 divisions on the disk proper, the inner face of said vertical flange and the upper face of said horizontal flange, a needle mounted in said casing and adapted to rotate independently of said disk and independent devices for arresting the disk and needle, substantially as described.

5. In a compass, the combination with the casing, of a pivotally-mounted disk within 55 the casing provided with a vertically-disposed flange terminating at its upper end in a horizontal flange, and provided with a scale of divisions on the disk proper, the inner face of said vertical flange and the upper face of 60 said horizontal flange, a needle mounted in said casing and adapted to rotate independently of said disk and independent devices for arresting the disk and needle, substantially as described.

6. In a compass, the combination with the compass-casing, provided with sighting devices, of a revoluble disk pivoted centrally within said casing, a weight secured to said disk eccentrically thereof, the compass-casing being also provided with division-markings, substantially as described. 70

7. In a compass, the combination with the compass-casing, provided with sighting devices, of a revoluble disk mounted in said casing, a needle mounted in said casing and adapted to rotate independently of said disk, independent arresting devices for said disk and needle, and a weight secured to said disk adjacent to its periphery, constructed to cause that portion of said disk to swing beneath its center, when the casing is held in 80 a vertical position, whereby the device may be used as a clinometer and the disk arrested for reading, substantially as described.

8. In a compass, the combination with the circular casing, of a needle mounted in said casing, a ring revolvably mounted on the exterior of said casing, and a level secured to said ring, substantially as described. 85

9. In a compass, the combination with the casing provided with sighting devices, of a ring revolvably mounted on said casing, a level secured to said ring, devices for adjusting said level in the plane of said ring and independent devices for adjusting said level perpendicularly to the plane of the ring, sub- 90 stantially as described.

10. In a compass, the combination with the casing provided with sighting devices, of a ring revolvably mounted on the casing, a level provided with bifurcated portions at each end, 95 sleeves engaging said bifurcated portions of the level and provided with eccentric apertures therethrough and adjusting-screws passing through said sleeves threaded into said ring and having portions engaging the bifurcated portions of said level, whereby said level 100 can be adjusted in the plane of the ring and also perpendicularly to the plane of the ring, substantially as described.

11. In a compass, the combination with the casing provided with sighting means and with an annular scale of divisions and a needle mounted in said casing, of a ring mounted revolvably on said casing and provided with index-marks, adapted to register with the divisions of said scale on the casing, and a bubble-tube or level secured to said ring, substantially as described. 115

12. In a compass, the combination with the casing, of a ring revolvably mounted thereon, 120 a level or bubble-tube secured to said ring, and a torch pivotally secured to said casing 125

130

and having a wick-tube extending to the top of the casing, whereby said bubble-tube may be rotated about the casing and said bubble-tube and the compass illuminated at any point, substantially as described.

13. In a compass, the combination with the casing, of a rotary disk mounted in said casing, a needle mounted in said casing and adapted to rotate independently of said disk, independent arresting devices for said disk and needle, folding diopters hinged to said casing and provided at their lower ends with bifurcated portions and at their upper ends with hook portions terminating in indicating-points, each of said diopters being provided with a sight-line, coinciding with its said indicating-point, substantially as described.

14. In a compass, the combination with the casing, of a rotary disk mounted in said casing, a needle mounted in said casing and adapted to rotate independently of said disk, independent arresting devices for said disk and needle, folding diopters, hinged to said casing and provided at their lower ends with bifurcated portions and at their upper ends with hook portions terminating in indicating-points, each of said diopters being provided with a sight-line, coinciding with its said indicating-point, one of said diopters being provided with a mirror above its bifurcated portion, substantially as described.

15. In a compass, the combination with the casing provided with a needle, of a support below said casing, pivotally connected with said casing, folding diopters pivoted to said casing, and adapted to be swung over and downwardly into the plane of the said support and provided with indicating-points, whereby the compass-casing may be revolved upon said support, the indicating-points of said diopters allowed to rest upon a paper and points taken directly therefrom in plotting, substantially as described.

16. In a compass, the combination with a casing, of a disk revolvably mounted therein, a weight secured eccentrically to said disk, a glass cover secured to said casing, flush with the upper surface thereof and a permanent sighting-line marked upon said glass cover, substantially as described.

17. In a compass, the combination with the casing, of a center pin threaded into the bottom thereof, a transparent cover for said casing, a needle revolvably mounted on said center pin beneath said cover, and having parts adapted to engage said cover to arrest the needle when the center pin is turned to raise the needle, said center pin having a part for engaging a part connected with the casing to prevent overwinding and thereby protect said center pin, substantially as described.

18. In a compass, the combination with the casing provided with a cover, of a vertically-adjustable center pin, and a needle having a bearing engaging said pin, said needle hav-

ing lateral spring portions extending above the said bearing, and adapted to engage the said cover before the said bearing, whereby the needle can be arrested without injury to the center pin or pivot-cup, substantially as described.

19. In a compass, the combination with the casing, of a rotary disk mounted within the casing and provided with a central bearing, a support for said bearing threaded into said casing, a center pin threaded in said disk-support, and extending through said disk, and a needle mounted upon said center pin and adapted to revolve freely, independently of said disk, substantially as described.

20. In a compass, the combination with the casing provided with a transparent cover, of a rotary disk mounted within the casing below said cover and provided with a central bearing, an adjusting-screw threaded into the bottom of the casing adapted to support the central bearing of said disk, and to raise said disk into contact with said cover to arrest said disk, said screw having a shoulder for engaging the casing to prevent overwinding, a center pin threaded into said adjusting-screw and extending through said disk, a needle mounted on said center pin and adapted to revolve freely, said needle having parts adapted to engage the said cover when the needle is raised by said center pin, to arrest the needle, said center pin having a shoulder to engage said adjusting-screw to prevent overwinding, substantially as described.

21. In a compass, the combination with the casing provided with a transparent top or cover, of a center pin having a threaded portion, and a shoulder to prevent overwinding and a needle having a central bearing engaging the center pin, and lateral spring portions extending therefrom and curved upward above the plane of the top of said bearing, substantially as described.

22. In a compass, the combination with the casing, of an annular torch-body, pivotally secured to the casing and provided with an upwardly-extending wick-tube, substantially as described.

23. In a compass, the combination with the casing, of an annular torch-body detachably and pivotally secured to the bottom of said casing and provided with a vertically-extending wick-tube, substantially as described.

24. In a compass, the combination with the casing provided with a transparent top or cover, of a disk pivotally mounted at its center within said casing, a needle in said casing, a revolvable ring on said casing, a level secured to said ring, folding diopters secured to said casing, and an annular torch pivotally secured to the bottom of the casing, forming a support therefor and provided with a vertically-extending wick-tube, substantially as described.

25. In a compass, the combination with the

easing provided with a vertically-adjustable center pin, extending through the bottom of said casing, a needle on said center pin, an annular torch-body pivotally secured to the bottom of the casing provided with a wick-tube extending above the top of the casing, said torch being provided with depending feet forming a support for the wick-tube and easing and protecting the outer end of the

center pin from injury, substantially as described.

In testimony whereof I affix my signature in the presence of two witnesses.

CHARLES C. RUEGER.
